UNITED STATES PATENT OFFICE.

JOSEPH PEYSER, OF MOUNT VERNON, NEW YORK, ASSIGNOR, BY MESNE ASSIGNMENTS, TO ACKERMANN MANUFACTURING COMPANY, OF WHEELING, WEST VIRGINIA, A CORPORATION OF WEST VIRGINIA.

SEAMING MECHANISM.

1,402,887.

Specification of Letters Patent. Patented Jan. 10, 1922.

Application filed December 26, 1918. Serial No. 268,259.

To all whom it may concern:

Be it known that I, JOSEPH PEYSER, a citizen of the United States, and a resident of Mount Vernon, in the county of West-
5 chester and State of New York, have invented certain new and useful Improvements in Seaming Mechanism, of which the following is a specification.

The present invention relates generally to 10 can heading machines and has more particularly reference to seaming mechanism.

The main object and feature of the invention resides in simple and efficient means for producing the in-and-out movement of a 15 seaming tool and whereby, at the same time, the parts may be properly lubricated.

In the accompanying drawings the invention is disclosed in several concrete and preferred forms, in which—

20 Figure 1 is a vertical sectional view of a seaming head embodying the invention on the irregular line 1—1 of Fig. 2.

Figure 2 is a bottom plan view of the parts shown in Fig. 1.

25 Figure 3 is a horizontal sectional view on the line 3—3 of Fig. 1.

Figure 4 is a vertical sectional view similar to Fig. 1 showing a modified form of the invention.

30 Figure 5 is a detail sectional view through one of the seaming tools on line 5—5 of Fig. 2.

It will be understood that in machines of 35 this character the work may be stationary or rotating, and that when the work is stationary the seaming tools travel in an orbit around the work and also have an in-and-out movement with respect thereto to perform the seaming operation, but that if the

40 work rotates the seaming tools are relatively stationary except for the in-and-out movement. It is customary to provide a seaming cam which has an effective circumferential displacement with respect to the seaming

45 tools equal to one revolution for each cycle of the machine. When the seaming tools travel in an orbit around the stationary work they make many revolutions to each cycle, and it is customary in cases of that

50 character to have the seaming cam also rotate a number of revolutions to each cycle of the machine, the number of revolutions of the seaming tools and seaming cams being unequal so that there is an effective dis-

placement of the cam with respect to the 55 tools of one revolution for each cycle of the machine. When the seaming tools are relatively stationary, except for the in-and-out movement, the seaming cam makes but one revolution to each cycle of the machine. 60

In the exemplification of the invention shown in Figs. 1, 2 and 3, the work is relatively stationary and the seaming tools travel in an orbit around the work, while in the exemplification shown in Fig. 4 the work 65 rotates and the seaming tools are relatively stationary, except for their in-and-out movement.

Considering first the form of the invention shown in Figs. 1, 2 and 3, *a* is a stationary 70 chuck that clamps the work against a pedestal (not shown). *o* is a rotating head making many revolutions to each cycle of the machine to which is secured a carrying member *c* having bottom and side walls as 75 shown. *b* indicates a seaming cam that rotates a number of revolutions to each cycle of the machine but here at a relatively slower speed than member *o*. This cam is above the bottom wall of carrying member 80 *c* and with it constitutes an oil container or reservoir to which oil may be fed from the top of the machine by way of the duct *b'*.

In the bottom wall of carrying member *c* are two radial slots *l* and in these slide reciprocating members *k* actuated from cam *b* and preventing egress of the oil from the container. The means for actuating each reciprocating member *k* consist of a cam roll *e* having a bolt *j* passing through member *k*. 90 On the underside of the bottom wall of carrying member *c* are two pivotally supported arms *d*. Each arm *d* has a pivot *d'* mounted in a bearing *d''* forming part of the side and bottom walls of member *c*. At one end of 95 each arm *d* is a seaming tool, the first operation roller being indicated by *d³* and the second operation roller by *d⁴*. The other end of each arm *d* is connected by means of a link *h* to one of the reciprocating members 100 *k*. In this instance link *h*, at one end, surrounds a bushing *i* carried by bolt *j* and extending through opening *n* communicating with slot *l* and at its other end a bolt *f* having an eccentric head *g* secures it to arm *d*. 105

It will be understood that by adjusting the eccentric head, the position of the seaming tool with respect to the work may be varied.

Member *c* is secured to member *o* by means of bolts *g*.

The upper face of the bottom wall of member *c* is provided with a circumferential oil groove *c'* and from this extends an oil duct *c''* to the groove *c'''* on arm *d* that in turn connects with the bearing of the seaming roller in a suitable manner.

In Fig. 4 the construction is substantially the same as in Figs. 1 to 3 except that here member *c* is bolted to a stationary portion of framework *p* and chuck *a* rotates.

Seaming cam *b* is provided with two sets of cam portions, each set consisting of an active portion 21 or 22 and an inactive portion 23 or 24, the arrangement being such that one active and one inactive portion are diametrically opposite to each other, just as seaming rollers *d³* and *d⁴* and cam rollers *e* are diametrically opposite to each other. Cam *b* is further provided with neutral portions 25 and 26 for the purpose of maintaining the seaming rollers, for a short period, in a neutral position substantially midway of their inner and outer positions.

The can to be seamed is inserted in the machine in any customary manner between chuck *a* and its co-operating element (not shown) this taking place when the seaming rollers are occupying their neutral position, rollers *e* being in engagement with cam portions 25 and 26.

Rotation of the cam *b* in the direction indicated by the arrow shown in Fig. 2 will now cause cam roller *e* of first operation roll *d³* to engage with neutral portion 26 and then with active portion 21 of the cam, cam roller *e* of the second operation roller *d⁴* engaging, at the same time, with neutral portion 25 and then with the inactive portion 23. This will cause *d³* to move toward the work to initially curl the cover and can, and *d⁴* to move away from the work. Continued rotation of cam *b* will now bring roller *e* of seaming roller *d³* into inactive portion 24, and roller *e* of seaming roller *d⁴* into active portion 22. This will cause *d³* to move away from and *d⁴* to move toward the work. After *d⁴* has completed its work the rollers *e* will enter neutral portions 25 and 26 and the finished can is removed and another one substituted.

In the foregoing description of the operation of the machine, the action which takes place during one-half revolution of cam *b* only has been set forth. It will be apparent

that during the remaining half of the revolution roller *e* of *d³* will engage inactive portion 23 and then active portion 22, while *e* of *d⁴* will engage active portion 21 and then the inactive portion 24 of cam *b* and that no seaming operation takes place during said second half revolution.

I claim:

1. Seaming mechanism comprising: a carrying member having two opposed radial slots, reciprocating members sliding in said slots, two pivotally supported members on said carrying member, a seaming tool on one end of each pivotally supported member, a seaming cam for actuating the reciprocating members, and two links each connected to the other end of one pivotally supported member and to one of the reciprocating members.

2. Seaming mechanism comprising: an oil container having bottom and side walls constituting a carrying member, a pivotally supported member on the lower side of the bottom wall of the carrying member, a seaming tool on the pivotally supported member, a seaming cam within the oil container and constituting one of the side walls thereof, a reciprocating member actuated by said cam and sliding in the bottom wall of said carrying member and means connecting the reciprocating member with the pivotally supported member.

3. Seaming mechanism comprising: a carrying member having bottom and side walls, a seaming cam forming a side wall above the bottom wall of the carrying member and constituting with the latter an oil container, a reciprocating member actuated by said cam and sliding in the bottom wall of said carrying member, a seaming tool, and connecting means between the reciprocating member and the seaming tool for imparting an in-and-out movement to said seaming tool.

4. Seaming mechanism comprising: a carrying member having bottom and side walls, a bearing in said side wall, a member pivotally supported on said bearing, a seaming tool carried thereby, a seaming cam above the bottom wall of the carrying member, and connections between the pivotally supported member and the seaming cam.

Signed at New York, in the county of New York, and State of New York, this 23rd day of December, 1918.

JOSEPH PEYSER.
